UNITED STATES PATENT OFFICE.

BRUNO V. NORDBERG, OF MILWAUKEE, WISCONSIN; HELENA C. NORDBERG EXECUTRIX OF SAID BRUNO V. NORDBERG, DECEASED.

VARIABLE-CAPACITY AIR COMPRESSOR.

Application filed September 8, 1923. Serial No. 661,649.

This invention relates to variable capacity compressors and particularly to that type in which the capacity of the compressor is varied by varying the point of cut-off of an inlet valve so as to vary the weight of gas drawn into the cylinder at each working stroke.

In a prior Patent, No. 900,418, granted to me October 6, 1908, I describe a mechanism of this general type in which a drop cut-off valve gear is used to control oscillating inlet valves to effect the desired function.

In my present disclosure, as in my prior patent above identified, I illustrate a valve gear forming the subject matter of Patent No. 680,667, dated August 13, 1901, for the reason that such valve gear is simple and satisfactory and is capable of giving a cut-off at any point in the working stroke. It should be noted, however, that any valve gear capable of giving a variable cut-off throughout a range substantially equal to the stroke may be used with the present invention and I therefore do not limit myself to the particular valve gear shown.

The arrangement disclosed in my Patent No. 900,418, has proved entirely satisfactory in cases where a single-ported inlet valve is used. When it becomes necessary to make the inlet valve double-ported, as is the case in large and in fast running compressors, some difficulty is encountered for the reason that the inlet valve must be quite large in diameter and must be provided with packing strips or other means to keep it tight.

This problem is complicated by the fact that when the compressor is running below full capacity there is a portion of the stroke in which the supply pressure predominates over cylinder pressure so that the packing of the inlet valve must seal against pressures acting alternately in reverse directions.

After the inlet valve cuts off or closes, the air in the cylinder expands and its temperature is lowered. In the ensuing compression stroke, the temperature again rises as the compression progresses and if there were no loss or gain of heat by the air, its temperature would be equal to that of the inlet air at the point where the compression pressure is equal to the inlet pressure. This condition is approximated so

long as no air leaks into the cylinder during the period of reduced pressure. If, however, there should be such a leak, the temperature would not be lowered sufficiently during the time the cylinder pressure falls below supply pressure, and this obviously tends to increase the heat developed during the ensuing compression period.

When the compressor works at low capacity the ratio of compression may be very high so that it is obvious that an addition of heat to the air at or near the beginning of the compression stroke would result in quite a high temperature at the end of compression. Hence, tight sealing of the inlet valve mechanism in both directions is vitally important.

In its broad aspects, the present invention contemplates the addition to a compressor having either automatic or positively actuated inlet valves of variable cut-off inlet controlling valves placed in the inlet ports, seating in the direction of inlet flow and acting to cut off variably the inlet flow. In its narrower aspects, the invention involves various details hereinafter fully discussed.

The main or ordinary inlet valves seal against outflow from the cylinder through the inlet ports, and the variable cut-off valves seal against the inflow of air from the supply to the cylinder. The main inlet valves are open throughout the entire suction stroke, as are the drop cut-off valves when the compressor operates at full capacity. When the drop cut-off valves close at part stroke, they are subjected to a preponderating supply pressure. Thus leakage is prevented in both directions and since each valve seals against pressure only in one direction, the valves can be simply constructed and can be made very free acting.

The construction outlined permits the application of the broad inventive principles of my Patent, No. 900,418, to large and fast running compressors.

A preferred embodiment of the invention is illustrated in the accompanying drawings, in which—

Fig. 1 is a view partly in section and partly in side elevation, showing the invention as applied to a double acting cylinder having positively actuated main inlet valves and automatic discharge valves;

Fig. 2 is a fragmentary section through the cylinder of Fig. 1, showing the valves of the head-end working space;

Fig. 3 is a view similar to Fig. 2 showing 5 automatic in lieu of positively actuated main inlet valves;

Fig. 4 is a view similar to Fig. 3 showing how an automatic inlet valve and a variable 10 cut-off inlet valve may be closely mounted to reduce the intervening port volume; and

Fig. 5 is a diagram representing a typical theoretical indicator card for compressors of the constructions illustrated in Figs. 1 to 4 when the cut-off valve closes at about half 15 stroke.

Referring first to Figs. 1 and 2, I shall describe those parts which are essentially similar to corresponding parts illustrated in Patent No. 900,418.

20 The engine frame is illustrated at 11, the crank shaft at 12, the cylinder at 13, and the wrist plate at 14. This wrist plate is illustrated as of the bell-crank type, and is provided with two arms 15 for directly 25 actuating the valve gear hereinafter described. The piston 16 is reciprocated in the cylinder 13 by means of the usual piston rod 17, which is connected through a connecting rod and crank (not shown) to the 30 crank shaft 12 in the usual manner. The piston rod 17 is provided with a tail rod or extension 18 as is common in the art.

35 Mounted on the crank shaft 12, at approximately 90° from the crank, is the main valve actuating eccentric 19, whose strap 20 is connected through the rod 21, rocker 22, and rod 23 to the wrist plate 14. A second eccentric 24, angularly displaced from the main eccentric 19, is also mounted on the 40 crank shaft 12, its strap 25 being connected by the rod 26, rocker 27, and rod 28, to oscillate a pendant link 29, fulcrumed at 30 on the frame 11.

45 The pressure regulator is essentially identical with that illustrated in Fig. 4 of Patent No. 900,418 and, so far as is material to the present invention, may be described as including a vertically slidable sleeve 31, which is urged upward by air pressure in the discharge chest of the compressor, and which is urged downward by a weight 32. The weight 32 is made in sections so that the discharge pressure against which the compressor is to work may be adjusted. The 50 sleeve 31 is formed with a groove 33 at its upper end which is engaged by a pivoted fork, not shown, positively connected with the arm 34. The arm 34 is fulcrumed at 35 and hence is swung upward by an increase 55 in discharge pressure and allowed to fall by a decrease.

60 The arm 34 is connected by links 36 and 37, which are pivoted together to the horizontal arm 38 of a three-armed lever whose other two arms 39 and 40 are connected to

the trip cams hereinafter described. The pivotal connection between the links 36 and 37 is guided by a short arm 41, also fulcrumed at 30, but movable independently of the pendant link 29.

70 The three-armed lever just mentioned is pivoted at 42 on the lower end of the pendant link 29, consequently, when the compressor is running, the link 29 and, with it, the three-armed lever is oscillated about the 75 pivot 30 by the eccentric 24. The rise and fall of the sleeve 31 merely rocks the three-armed lever on the fulcrum 42. Since the arm 39 projects upward from the arm 38, and the arm 40 downward, and since the trip cams are reversely arranged as hereinafter mentioned, the movements of the sleeve 31 affect both trip cams equally and in the same sense.

80 Referring now to Fig. 2, the discharge valves will be described with reference to that used at the head end of the cylinder. Any desired type of discharge valve might be used, but I have chosen for illustration an automatic valve of the reed type, in which a plurality of thin resilient reeds 43 are mounted over the apertures in grids 44. These grids are formed in a unitary cylindrical plug or insert 45, which is inserted 85 in an opening in the cylinder head and which is retained therein by a removable bonnet 46 (see Fig. 1).

85 The main inlet valve 47 is shown as an ordinary double-ported valve of the Corliss or oscillating type. It is positively actuated 90 in the usual manner by an arm 48 fixed on its stem and connected by a link 49 with one arm 15 of the wrist plate. A similar, but reversely arranged, valve is used at the crank end of the cylinder. These main inlet valves 47 are timed to remain open throughout the suction stroke and they are so mounted that they are held to their seats by cylinder pressure when this preponderates over inlet pressure.

110 Mounted as close to the inlet side of each main inlet valve 47 as is possible is a second double-ported valve 50, of the oscillating or Corliss type, which is so arranged as to be urged to its seat when the pressure of supply predominates. This valve 50 is chosen as typical of the class of variable cut-off valves and, in fact, I prefer for this duty a valve of the drop cut-off type. It 115 may be actuated by any valve gear which will give a range of variable cut-off coextensive with the stroke. For this purpose I illustrate the valve gear described in my two prior patents and hence need describe it only 120 generally.

125 The valve closing arm 51 is fast on the stem of the valve 50, and is urged in a valve closing direction by a plunger in the dash pot 52 connected by the rod 53 with the arm 51. The valve opening arm 54 is 130

mounted to oscillate coaxially with the valve 50 and is connected by a link 55 with the arm 48 of the corresponding main inlet valve.

5 The trip arm 56 is pivoted at 57 on the valve opening arm 54 and carries a latch block 58 which coacts in the usual manner with a latch block 59 on the valve closing arm. The trip arm 56 is provided with a 10 crank pin 60 which engages in the trip cam groove 61. The groove 61 is formed in a cam plate 62 pivoted at 63 on the valve opening arm and oscillates thereon through a link 64. This link 64 is connected to the 15 corresponding one of the arms 39-40 of the three-armed lever. Consequently, the trip cams 61 are oscillated by the eccentric 24 under the control of the governor sleeve 31.

20 The valve 50 is so timed as to close at the end of the suction stroke, i. e., simultaneously with the valve 47 whenever the compressor is working at full capacity. Under this condition the latch is not tripped 25 by the trip cam. When the compressor works at reduced capacity, the valve 50 is tripped closed while the valve 47 remains open. The closing of the valve 50 causes cylinder pressure to drop below the pressure 30 of supply and consequently the valve 50 is held to its seat by inlet pressure. During the compression stroke both valves are closed.

35 The possibility of linking the two valves together, as shown in Fig. 1, arises from the fact that the two valves are timed together under the conditions of full stroke operation.

40 As suggested, it is possible to substitute automatic valves for the mechanically operated inlet valves 47. Fig. 3 shows a simple manner of modifying the structure of Fig. 2 to this end. The port formation is slightly changed and for the valve 47 is substituted 45 a cylindrical plug 70 having grids 71 and reed valves 72. This valve is essentially identical with the discharge valve structure already described and, like the discharge valve, is held in place by a bonnet. The plug 70 of course is fixed in position. Consequently, the rocker arms 48 are omitted and the 50 valve opening arms 54 are connected directly to the wrist plate instead of indirectly through connection with the arm 48, as in Fig. 1. This change involves a different proportioning of the linkage to secure the proper timing of the valve 50, but this is a matter of design, which will be obvious to those skilled in the art.

60 One difficulty which is encountered in the use of automatic inlet valves is clearly illustrated in Fig. 3. This is the large port volume between the reed valves 72 and the drop cut-off valve 50 which produces a variable clearance space and hence affects the

operation of the compressor. The structure illustrated in Fig. 2 has a much smaller port volume intervening between the valves.

In Fig. 4, I show a rearrangement of the structure of Fig. 3, in which the grids 71 and reed valves 72 are formed in a relatively large plug 73, which is further provided with a ported seat to receive the drop-cut-off valve 50. The plug 73 in this construction is of course fixed in place and the valve opening 75 arm 54, which actuates the valve 50, is connected directly to an arm 15 of the wrist plate, as described in connection with Fig. 3.

The diagram of Fig. 5 shows a theoretical card when cut-off by valve 50 occurs at 80 about mid-stroke. Air enters the compressor at a pressure P_1 and is discharged at a higher pressure P_2 . At the beginning of the suction stroke at a , the inlet valves are closed and the cylinder pressure is P_2 . The air 85 expands back to the inlet pressure P_1 and reaches that pressure at b , at which point the inlet valves open. Preferably, the cut-off valve 50 opens a little earlier than the main inlet valve. Air now enters the compressor 90 at pressure P_1 to the point c . Here the cut-off valve 50 closes.

The volume at c is the volume $a'c$ plus the clearance, including the port volume to the drop cut-off valve 50. At the end of the suction stroke the pressure in the cylinder has dropped to some reduced pressure P_3 at d . During the expansion $c'd$, there is a 95 partial vacuum in the cylinder and leakage into the cylinder is prevented solely by the cut-off valve 50, which is held to its seat by the preponderance of pressure P_1 .

The compression stroke commences at d . Since the inlet valve closes at d the volume undergoing compression is the piston displacement plus the clearance to the main inlet valve, and such clearance is less than the clearance to the variable cut-off valve 50. The compression, up to the point e , takes place while the pressure in the cylinder is 100 below the inlet pressure P_1 . During this period the cut-off valve 50 continues to seal against the entrance of air, the main suction valve being ineffective for this function because it seats only under preponderating cylinder pressure.

105 Since the expansion from c to d takes place with a larger clearance than the compression from d to e , the compression pressure rises faster. This makes the volume $b'e$ greater than the volume $b'c$ as shown. The shaded area $c'd'e$ in the diagram will 110 therefore represent work done by the compressor. The volume $c'e$ and hence the shaded area, just mentioned, is greater or less according to the port volume between the main inlet valve and the variable cut-off valve 50. I prefer the positively actuated type of main cut-off valve, shown in Figs. 1 and 2, for the reason that such intervening 115

120 125 130

port volume can be made very small with this type of valve.

From *e* compression continues to *f*, at which point pressure P_2 is attained in the cylinder. The discharge valve then opens and discharge occurs along the line *f a* at pressure P_2 .

The volume drawn into the compressor under the conditions described is equal to *b e* and the work necessary to compress it is represented by the area *a b c d e f*.

What is claimed is:

1. The combination of a compressor having inlet and discharge valves; a variable cut-off valve arranged to be held to its seat by inlet pressure and to control the flow of gas through the inlet valve; and means for varying the point of cut off of said cut-off valve.

2. The combination of a compressor having an inlet valve, the latter being arranged to be held to its seat by preponderating cylinder pressure; a variable cut-off valve arranged to be held to its seat by preponderating supply pressure and to control the flow through said inlet valve; and means for varying the point of cut off of said cut-off valve.

3. The combination of a compressor having an inlet valve arranged to be held to its seat by preponderating cylinder pressure; a variable cut-off valve situated on the inlet side of said inlet valve and arranged to control the flow thereto and to be held to its seat by preponderating supply pressure; and means for varying the point of cut-off of said cut-off valve.

4. The combination of a compressor having an inlet valve arranged to be held to its seat by preponderating cylinder pressure; a variable cut-off valve situated on the inlet side of said inlet valve and arranged to control the flow thereto and to be held to its seat by preponderating supply pressure; and pressure controlled automatic means for varying the point of cut off of said cut-off valve.

5. The combination of a compressor having an inlet valve of the mechanically actu-

ated type; an inwardly seated variable cut-off valve arranged to control flow through said inlet valve; mechanical means serving normally to actuate said valves in unison; and a pressure regulator operable by the rise of discharge pressure above normal and serving to advance the closing of said cut-off valve relatively to said inlet valve.

6. The combination of a compressor having an inlet valve of the mechanically actuated type; a cut-off valve arranged to control the flow through said inlet valve; mechanical means for actuating said valves substantially in unison; a releasing and closing mechanism serving to release said cut-off valve from said actuating means and cause it to cut off in advance of the closing of said inlet valve; and pressure controlled means serving to vary the point of such cut off.

7. The combination of a compressor having an inlet valve of the mechanically actuated type; a reversely seated cut-off valve also controlling the inlet, and situated close to and in advance of the inlet valve; mechanical means for actuating said valves substantially in unison; a drop cut-off mechanism arranged to close said cut-off valve in advance of the closing of said inlet valve; and pressure controlled means serving to vary the point of action of said drop cut-off mechanism.

8. The combination of a compressor having an inlet valve of the mechanically actuated oscillating type; a reversely seated cut-off valve of the oscillating type also controlling the inlet and situated close to and in advance of the inlet valve; a variable drop cut-off mechanism for said cut-off valve operable at substantially any point in the working stroke; actuating means arranged to operate said valves substantially in unison; and pressure controlled means operatively related to said drop cut-off mechanism and serving to advance variably the point of cut-off of the cut-off valve.

In testimony whereof I have signed my name to this specification.

BRUNO V. NORDBERG.
